UNITED STATES PATENT OFFICE

DOUGLAS S. CAMPBELL, OF CLEVELAND, OHIO, ASSIGNOR TO THE POCOHONTAS OIL COMPANY, A CORPORATION OF OHIO

DESIGN FOR A SIGN

Application filed August 22, 1930. Serial No. 36,731. Term of patent 14 years.

To all whom it may concern:

Be it known that I, DOUGLAS S. CAMPBELL, a citizen, of the United States, residing in Cleveland, in the county of Cuyahoga and the State of Ohio, have invented a new, original, and ornamental Design for Signs, of which the following is a specification, reference being had to the accompanying drawing, forming a part thereof.

The figure is a perspective view of a sign embodying my new design.

The sign is of the kind whereupon the design appears on both sides of the sheet.

I claim:—

The ornamental design for a sign as shown and described.

DOUGLAS S. CAMPBELL.
